UNITED STATES PATENT OFFICE

ROBERT W. McCREADY, OF INGERSOLL, ONTARIO, CANADA

DESIGN FOR A RESTAURANT

Application filed June 29, 1929, Serial No. 31,875, and in Canada March 27, 1929. Term of patent 3½ years.

To all whom it may concern:

Be it known that I, ROBERT W. McCREADY, a subject of the King of Great Britain, residing in the town of Ingersoll, in the county of Oxford, in the Province of Ontario, Canada, have invented a new, original, and ornamental Design for Restaurants, of which the following is the specification, reference being had to the accompanying drawing, forming part thereof.

The figure is a perspective view of a restaurant, showing my new design.

I claim:

The ornamental design for a restaurant, as shown.

ROBT. W. McCREADY.
